(57) **CLAIM**

The ornamental design for a blower housing with high profile air cleaner, as shown and described.

DESCRIPTION

FIG. 1 is a perspective view of a blower housing with high profile air cleaner showing our new design;

FIG. 2 is a top view thereof;

FIG. 3 is a rear view thereof;

FIG. 4 is a right side view thereof;

FIG. 5 is a left side view thereof;

FIG. 6 is a front view thereof; and,

FIG. 7 is a bottom view thereof.

The broken lines showing in the figures are for purposes of illustrating portions of the engine blower housing with high profile air cleaner (or associated components) only and form no part of the claimed design.
